CARPET.

No. 17,502.

Patented July 26, 1887.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,502, dated July 26, 1887.

Application filed June 18, 1887. Serial No. 241,806. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design. My design consists of several groups of leaves and flowers and stems disposed irregularly over the surface of the carpet.

Group A (shown at the middle of the photograph) has at its center a number of scroll-shaped leaves, two of them diverging and curved and a third inclosing an expanded leaf. From this center stems project on different sides, bearing figures resembling leaves and buds and fruit.

Group B (shown at the upper right-hand and lower left-hand portions of the photograph) is composed of a number of fan shaped figures or leaves thrown together irregularly, with projecting stems supporting flowers and leaves.

Group C (shown at the upper left-hand and lower right-hand portions) consists of a bell-shaped flower, from the center of which projects a scroll-shaped leaf bearing small leaf-and-flower figures. Between these groups are scattered a few unconnected flowers and leaves irregularly bunched, all as clearly shown in the photograph.

What I claim as new, and desire to secure by Letters Patent, is—

The design for carpets, consisting of the design, substantially as shown.

HENRY HUNT.
